Primary Examiner — Khawaja Anwar*Assistant Examiner* — Megan Tiana Rakos(74) *Attorney, Agent, or Firm* — Legalforce RAPC Worldwide(57) **CLAIM**

The ornamental design for a belly speaker, as shown and described.

DESCRIPTION

FIG. 1 is a front top-right side perspective view for a belly speaker, showing my new design;

FIG. 2 is a rear bottom perspective view of FIG. 1 thereof;

FIG. 3 is a front elevational view of FIG. 1 thereof;

FIG. 4 is a rear elevational view of FIG. 1 thereof;

FIG. 5 is a left side elevational view of FIG. 1 thereof; the right side elevational view being a mirror image;

FIG. 6 is a top plan view of FIG. 1 thereof; and,

FIG. 7 is a bottom plan view of FIG. 1 thereof.

The broken lines indicate unclaimed portions of the belly speaker and form no part of the claimed design.

1 Claim, 7 Drawing Sheets(56)
